Primary Examiner — Ryan Harvey(74) *Attorney, Agent, or Firm* — Procopio Cory Hargreaves and Savitch LLP(57) **CLAIM**

The ornamental design for a adjustable stationary cycle, as shown and described.

DESCRIPTION

FIG. 1 is a perspective view of the adjustable stationary cycle;

FIG. 2 is a front elevation view of the adjustable stationary cycle;

FIG. 3 is a rear elevation view of the adjustable stationary cycle;

FIG. 4 is a left side elevational view of the adjustable stationary cycle;

FIG. 5 is a right side elevational view of the adjustable stationary cycle;

FIG. 6 is a top plan view of the adjustable stationary cycle; and,

FIG. 7 is a bottom plan view of the adjustable stationary cycle.

Any broken lines shown in FIGS. 1-7 are included for the purpose of illustrating environmental elements only and form no part of the claimed design.

1 Claim, 7 Drawing Sheets(56)
